UNITED STATES PATENT OFFICE.

WILLIAM M. NORCROSS, OF PHILADELPHIA, PENNSYLVANIA.

CAR-SEAT.

SPECIFICATION forming part of Letters Patent No. 793,605, dated June 27, 1905.

Application filed October 11, 1901. Serial No. 78,307.

To all whom it may concern:

Be it known that I, WILLIAM M. NORCROSS, a citizen of the United States, residing at Philadelphia, in the county of Philadelphia and State 5 of Pennsylvania, have invented a certain new and useful Improvement in Car-Seats, of which the following is a description.

The invention relates to that type of car-seat in which are employed two independently pivoted seats or chairs mounted upon a common pedestal and capable of being moved together in the arc of a circle, each chair at the same time turning upon its pivot, so as to face in a direction opposite that in which it faced prior to the interdependent movement of both 15 chairs together.

The object of the invention is to provide a seat of this type consisting of few and simply-constructed parts of maximum strength and 20 durability and capable of ready and easy assemblage.

A further object of the invention is to provide simple and efficient means for locking the chair in either of its two positions.

25 In carrying out the invention I employ a common pedestal or support, upon which is pivotally mounted a yoke provided with bearings designed to receive downwardly-projecting spindles either secured to the chair-bottoms or forming part of the spiders upon which the chairs are mounted. Also mounted upon such pedestal and keyed or otherwise secured thereto I employ a reversing-arm extending on either side of said pedestal and co- 30 acting with the chair-bottoms or with the spiders thereof in order to turn such bottoms or spiders upon their pivots as the yoke is moved to turn the entire seat structure upon the pedestal in the arc of a circle.

40 In the present embodiment of the invention the connection between the reversing-arm and the chairs consists of pins or studs at either end of said arm coacting with elongated slots formed in the pivoted chair-spiders upon 45 which the chairs are mounted. The parts are so proportioned and arranged relatively to each other as that in one of the positions of the chairs such pins or studs will come to rest in the extreme outer ends of the slots in the 50 spider-arms. In the turning operation such

pins or studs move within such slots toward the pivotal point of the spiders, causing such spiders to be turned upon their pivots, and when the turning operation has been completed, bringing such pins or studs again to 55 rest in the extreme outer ends of said slots, all said parts coacting positively and without unnecessary wear and rattling.

In the embodiment of the invention here alluded to a locking mechanism is provided, 60 preferably operable from a point adjacent to the edge of one or both of the seat-bottoms and coacting with the slots in the chair-spiders and with pins or studs carried by the reversing-arm, so as to preclude the movement of 65 said pins or studs in said slots, and thereby lock both chairs of the seat rigidly in one or the other of their two positions.

It will thus be seen that in its simplest form, as above described, and assuming the chairs 70 to be provided with the slotted spiders alluded to, the entire structure comprises but three parts in addition to the locking mechanism—*i. e.*, the pedestal, the pivoted yoke, and the reversing-arm. These parts combined with 75 the chairs, as above indicated, form an exceedingly simple, durable, and compact seat structure capable of being assembled with the greatest ease and meeting all the requirements of practical use in a most efficient manner.

The invention is illustrated in the accompanying drawings, in which—

Figure 1 is an elevation of a car-seat embodying the present invention. Fig. 2 is a 85 plan view thereof, the chairs and their attached backs being removed; and Fig. 3 is a section on the line 3 3 of Fig. 2.

Referring to these drawings, in which similar letters denote corresponding parts, A designates the support or pedestal provided, if 90 desired, with a bottom flange for attachment to the floor of the car. Pivoted upon this pedestal so as to swing in a horizontal plane thereon is a yoke B, provided at either end 95 with a housing or bearing b to receive the spindles c of the chair-spiders C. Each of the chair-spiders is preferably formed integral and comprises in addition to the spindles c and shoulder c' outwardly-extending arms c², (here 100

shown as four in number,) each of such arms being provided, preferably near its ends, with screw-holes or other means for securing the spider-arms to the chair-bottoms. One of the 5 arms c^2 of each of the chair-spiders is provided with an elongated slot c^3 , the office of which will be presently explained.

D designates a reversing-arm centrally perforated at d and mounted upon the upper end 10 of the pedestal A. It is here shown as keyed at d' to such pedestal, although obviously other means may be employed for the same purpose—such, for instance, as a set-screw passing through the hub of said arm. Each end 15 of the arm D is provided on its upper side with a pin or stud d^2 of such size as to fit snugly within the slots c^3 , formed in one of the arms c^2 of each of the spiders C and to move within such slots for the purpose of effecting the 20 reversal of the chairs. If desired, said pins or studs may carry rolls operating within said slots.

The turning and reversing operation can 25 probably be best understood from Fig. 2, in which one position of the chair is illustrated in full lines, its other position being indicated by a dotted line passing through the center of the pedestal. Obviously if pressure in a horizontal plane be applied to one of the chairs 30 the yoke B will be turned upon the pedestal A. The reversing-arm D, however, being keyed to such pedestal remains stationary. As the yoke is revolved upon its pivot the pins or studs d^2 of the reversing-arm D move in 35 the slots c^3 toward the center of the chair-spiders, and as such movement progresses said spiders are turned upon their pivots in the yoke B. In the intermediate position between the two positions of rest the pivots d^2 40 will have progressed in the slots c^3 substantially to the inner ends thereof, when the pivotal points of the spiders, that of the yoke B, and the pins or studs d^2 will lie in the same plane. As the movement continues the pins 45 or studs d^2 , moving outwardly in the slots c^3 , continue the turning movement of the spiders and finally come to rest in the outer ends of the slots, having in their inward and outward excursion turned the spiders (and therefore 50 the chairs mounted thereon) through approximately one hundred and eighty degrees of a circle and causing them to face in a direction opposite that in which they faced prior to the turning movement.

55 In the present embodiment of the invention it is contemplated that the extreme movement of the yoke B and of the chair-spiders shall be limited by the dimensions of the slots c^3 , the position of rest being determined when 60 the pins or studs coat with the outer ends of such slots. Obviously no further movement in the turning direction can be effected. Unless, however, means be provided for locking the structure in this position the reverse movement may readily be effected, either by pres-

sure upon the chairs or by the jarring of the car. I provide, therefore, a locking mechanism coacting with one or both of the chairs and with the reversing mechanism above described. As here shown, this consists of a 70 tongue E, pivoted at e upon one of the spiders and provided with a rock-shaft e' (preferably carried by straps e^2) and handpieces e^3 , located adjacent to the edges of the chair-bottom and immediately below the same. The 75 tendency of the tongue E under the influence of gravity is to rest in the slots c^3 , and it is of such length as that when the seat is in one or the other of its two positions and the pins or studs d^2 of the reversing-arm D are therefore located in the outer ends of the slots c^3 it will bear against the inner surface of one of such pins and lock it in this position, as clearly indicated in Fig. 3. In order to release the locking mechanism and effect the reversal of the seat, it is only necessary to grasp the chair-bottom and at the same time the 80 handpieces e^3 . The latter being pressed upwardly and pressure applied to the seat-bottom in the direction indicated by the arrow, 85 Fig. 2, the seat may be swung upon its pedestal, as hereinabove described. At the end of the swinging movement the tongue E, falling by gravity into the slot c^3 , automatically locks the structure in the new position. 90

Importance is attached to the facility with which the chairs may be reversed, so as to face in a different direction, upon movement of the yoke in a very small arc. Heretofore, so far as I am aware, in twin chair structures 100 pivoted upon a yoke the chair-operating connections have been so arranged that in order to turn such chairs to a new facing position the yoke must be swung entirely around, as in the construction disclosed in Letters Patent No. 595,624, granted December 14, 1897. The objection to this resides not only in the necessity for excessive movement of the yoke, but also in the fact that in order to provide for such movement additional space within 105 the car must be sacrificed. In my device the reversal of the chairs is accomplished not by swinging the device as a whole bodily around the pivotal point through a very considerable arc of a circle, but by turning it through a 110 very limited arc, the connections thereupon reversing the chairs interdependently with the movement of said beam to the new facing direction. This will be clear from an inspection of Fig. 2, indicating by means of the 115 full-line position of the yoke (illustrating one facing direction of the chairs) and the dotted line indicating the axis of the yoke (in the other facing direction) the very limited arc through which the yoke is moved in order to 120 effect the complete and interdependent reversal of the chairs. 125

What I claim is—

1. In a reversible car-seat, the combination with a pivoted yoke, of two chairs pivotally 130

- mounted thereon and provided with members having elongated slots, and a reversing-arm coacting with said slots, substantially as set forth. 55
- 5 2. In a reversible car-seat, the combination with a pedestal, of a yoke pivoted thereon, two chairs pivotally mounted upon said yoke and provided with members having elongated slots, and a reversing-arm rigidly secured to said pedestal and coacting with said slots, substantially as set forth. 60
3. In a reversible car-seat, the combination with a pedestal, of a yoke pivoted thereon, two chairs pivotally mounted upon said yoke and provided with members having elongated slots, and a reversing-arm rigidly secured to said pedestal and provided at or near its ends with means coacting with said slots, substantially as set forth. 65
- 5 4. In a reversible car-seat, the combination with a pedestal, of a yoke pivoted thereon, two chairs pivotally mounted upon said yoke, members movable with said chairs and having elongated slots, and a reversing-arm rigidly secured to said pedestal and having projections coacting with said slots, substantially as set forth. 70
- 5 5. In a reversible car-seat, the combination with a pedestal, of a yoke pivoted thereon, two chair-supports pivotally mounted upon said yoke, slots formed in said supports, and a reversing-arm secured to said pedestal and coacting with said slots, substantially as set forth. 75
- 35 6. In a reversible car-seat, the combination with a pedestal, of a yoke pivoted thereon, two chair-supports pivotally mounted upon said yoke, slots formed in said supports, and a reversing-arm secured to said pedestal and having pins or studs coacting with said slots, substantially as set forth. 80
- 40 7. In a reversible car-seat, the combination with a pivoted yoke, of two chairs pivotally mounted thereon and provided with members having elongated slots, a reversing-arm coacting with said slots, and mechanism adapted to lock the seat in one or another position, substantially as set forth. 85
- 45 8. In a reversible car-seat, the combination with a pivoted yoke, of two chairs pivotally mounted thereon and provided with members
- having elongated slots, a reversing-arm coacting with said slots, and mechanism coöperating with said arm and slots to lock the seat in one or another position, substantially as set forth. 55
9. In a reversible car-seat, the combination with a pivoted yoke, of two chairs pivotally mounted thereon and provided with members having elongated slots, a reversing-arm coacting with said slots, a locking-tongue pivoted adjacent to said slots and coöperating with said arm, and means for controlling the movement of said tongue, substantially as set forth. 60
10. In a reversible car-seat, the combination with a pivoted yoke, of two chairs pivotally mounted thereon and provided with members having elongated slots, a reversing-arm coacting with said slots, a locking-tongue pivoted adjacent to said slots and coöperating with said arm, and a rock-shaft and handpiece for controlling the movement of said tongue, substantially as set forth. 70
11. In a reversible car-seat, the combination with a pedestal, of a yoke pivoted thereon, two chairs pivotally mounted upon said yoke, members movable with said chairs and having elongated slots, a reversing-arm secured to said pedestal, projections carried thereby and operating within said slots, and tongues, provided with actuating mechanism, hinged adjacent to and operating within said slots to determine the movement of said projections therein, substantially as set forth. 80
12. In a reversible car-seat, the combination with a pivoted yoke, of two chairs pivotally mounted thereon, a reversing-arm, and slot-and-pin connections between said arm and said chairs, substantially as set forth. 90
13. In a reversible car-seat, the combination with a pivoted yoke, of two chairs pivotally mounted thereon and movable interdependently, a reversing-arm common to both chairs, and slot-and-pin connections between said arm and said chairs, substantially as set forth. 95
